UNITED STATES PATENT OFFICE.

FREDERICK W. SPENCER, OF IONIA, MICHIGAN, ASSIGNOR OF ONE-FOURTH TO THOMAS M. KOWALSKI, OF IONIA, MICHIGAN.

AUTOMOBILE-RADIATOR.

1,156,325.

Specification of Letters Patent. Patented Oct. 12, 1915.

Application filed March 28, 1914. Serial No. 827,929.

To all whom it may concern:

Be it known that I, FREDERICK W. SPENCER, a citizen of the United States, residing at Ionia, in the county of Ionia and State 5 of Michigan, have invented certain new and useful Improvements in Automobile-Radiators, of which the following is a specification.

This invention relates to automobile radiators, and has as its object to provide a radiator which will be light in weight, although exceptionally strong and durable, and which will have a maximum radiating area as compared with the space occupied by 10 the radiator as a whole.

The radiator embodying the present invention is of that type comprising a number of assembled sections, and it is an aim of the invention to so construct the sections 20 that they may be readily assembled and disassembled, and may be added to or removed as desired.

In the accompanying drawings: Figure 1 is a front elevation of the radiator embodying the present invention. Fig. 2 is a vertical sectional view therethrough on the line 2—2 of Fig. 1. Fig. 3 is a sectional perspective view of one upper corner of the radiator. Fig. 4 is a similar sectional view 30 on the line 4—4 of Fig. 1.

Corresponding and like parts are referred to in the following description and indicated in all the views of the accompanying drawings by the same reference characters.

As before stated, the radiator is made up of a number of sections, and these sections are of counterpart form, except for certain minor details to be presently explained. In the drawings but two of the sections are 40 shown, but, as will be presently made clear, any desired number may be employed, depending of course upon the character of engine employed.

In the drawings, one of the sections is indicated in general by the letter A and the other by the letter B, the section A being the forward section and the section B being the rear or inner section. Each section comprises essentially a hollow frame-like body, 50 the front wall of which is indicated by the numeral 1, the rear wall by the numeral 2, and the surrounding, or top, bottom and side walls, by the numeral 3. The forward section A is provided in its top with a filling 55 spout 4, having a cap closure 5, and the sec-

tion B has led into it through its rear wall, a pipe 6, which leads from the water jacket of the engine, and a pipe 7, which leads from the radiator to the said water jacket, the pipe 6 being located near the top of the radiator and the pipe 7 being disposed near the bottom of the radiator, as is customary. Each section is, of course, provided with an inner wall 8 which is spaced from the wall 3, and fitted at their upper and lower ends in 60 the top and bottom walls of the inner wall 8 respectively, are tubes 9; the tubes of each section being preferably arranged in staggered relation, as clearly shown in Fig. 4 of the drawings, and each tube having arranged upon it a number of radiating disks 10, which may be circular or of any other desired outline; or, if desired, a spiral or similar radiating flange may be provided upon each tube. It is preferable that a 70 screen 11 be secured upon the front of the forward section A, so as to protect the tubes of the radiator from dust and dirt.

The front wall of the forward section A is formed adjacent its corner with an opening 12, and the rear wall of the said section is formed adjacent each corner with an opening 13, tubes 14 being secured within the hollow body of the section and registering at their ends with the said openings 12 and 13. These tubes are provided each with a number of openings 15, the purpose of which will be presently made clear. In a like manner, the forward wall of the section B is formed near each corner with an opening 16 and its rear wall is similarly formed with openings 17, the tubes 18 corresponding to the tubes 14, being arranged within the hollow body of the said section B and registering at their ends with the said 80 openings 16 and 17. When the sections are assembled, they are disposed in the manner shown in Figs. 2, 3 and 4, and bushings 19 are fitted in the adjacent ends of the corresponding tubes 14 and 18 and serve to establish communication between the said tubes. If desired, however, the bushings 19 may be secured in the tubes 18 and may project beyond the forward face of the rear section B, so as to fit within the rear ends 90 of the tubes 14, when the sections are assembled. Prior to thus assembling the sections, packing gaskets or washers 20 are fitted one upon each of the bushings, so that when the sections are clamped together, the washers 110

20 will be compressed and a water tight joint will be effected between the sections at the point of location of the said tubes. As a means for clamping the sections together, tie-bolts 21 are fitted through the washers 22 and 23 disposed respectively against the forward face of the section A, and rear face of the section B, the said washers closing respectively the openings 12 and 17, and a 5 nut 24 is threaded on to each tie-bolt and bears against the respective washer 23, the head of the bolt bearing against the corresponding washer 22, and the shank of the bolt extending through the tubes 14 and 18 10 and the said bushing 17.

From the foregoing, it will be apparent that water entering the section B through the pipes 6 which fill the hollow body of the section and its radiator tube 9, will flow 20 through the openings in the tubes 18 and through these tubes and the bushing 19 into the tube 14, from which it will pass through the openings 15 into the hollow body and tubes of the section A, the return flow being 25 through the lower ones of the tubes 14 and 18 and out through the pipe 7.

The washers 22 and 23 are preferably provided with reduced portions 22' and 23' which fit within the openings 12 and 17 respectively, and serve to prevent leakage by completely closing these openings. When it is desired to add to the number of sections, any additional number of sections B may be employed, which supplemental sections are, 30 however, not provided with openings for the inlet pipe 6 and outlet pipe 7. Any suitable means may be provided for securing the radiator to the frame of the machine, as for example, threaded studs 25 which project 35 from the lower end of the section A.

Having thus described the invention, what is claimed as new is:

1. A radiator comprising a plurality of juxtaposed similar hollow frame-like sec-

tions having openings in their front and rear 45 walls in coincident relation, a plurality of tubes connecting the inner walls of each of the sections, other tubes between the front and rear walls of each of the sections in line with the openings therein and having their 50 extremities formed with outer flanges, bushings extending across the joints formed between the sections and entering the opposing ends of the flanged tubes, gaskets mounted upon the bushings, washers closing the 55 openings in the outer walls of the sections, and tie-bolts passing through the washers and the flanged tubes and connecting the several sections.

2. A water cooling radiator for internal 60 combustion engines, the same comprising a plurality of juxtaposed similar hollow frame-like sections having openings in their front and rear walls in coincident relation, tubes extending across the space formed between the inclosing hollow members of each of the sections and connecting the inner walls thereof, other tubes disposed between the front and rear walls of each of the sections in line with the openings formed in such 70 walls and having their extremities outwardly flanged and such tubes having openings in their sides, bushings extending across the joints formed between the sections and having their ends inserted in the opposing ends of adjacent flanged tubes, gaskets mounted upon the bushings between the sections, washers closing the openings in the outer walls of the sections, and tie-bolts passing through the washers, flanged tubes and 75 bushings and connecting the several parts.

In testimony whereof I affix my signature in presence of two witnesses.

FREDERICK W. SPENCER, [L. S.]
